(57) CLAIM

The ornamental design for an oven mitt, as shown and described.

DESCRIPTION

FIG. 1 is a frontal perspective view of an embodiment of an oven mitt of the instant design;

FIG. 2 is a front elevation view of the oven mitt of FIG. 1.

FIG. 3 is a rear elevation view of the oven mitt of FIG. 1.

FIG. 4 is a left side elevation view of the oven mitt of FIG. 1.

FIG. 5 is a right side elevation view of the oven mitt of FIG. 1.

1 Claim, 5 Drawing Sheets
